W. F. HUDSON

BABY DEVELOPMENT DEVICE

Original Filed May 13, 1925

William F. Hudson,
Inventor

By William J. Jackson

Attorney

UNITED STATES PATENT OFFICE.

WILLIAM F. HUDSON, OF PHILADELPHIA, PENNSYLVANIA.

BABY-DEVELOPMENT DEVICE.

Application filed May 18, 1925, Serial No. 29,866. Renewed May 6, 1927.

This invention, generally stated, relates to amusement and exercising devices for children of tender age and relates more especially to the type of device disclosed in my co-pending application for patent Serial No. 633,093, filed April 19, 1923.

While the device disclosed in my said application is admirably adapted for the purposes intended practice has dictated that at certain periods it is highly desirable to maintain the device in a state of rest in contradistinction to its normal tendency to rock.

Therefore, the leading object of the present invention may be said to reside in the provision of means forming part of the base of the device which at desired times may be opened up to function as a stabilizing medium, particularly when a tray, also forming part of the present invention, is attached to the seat of the device. Other and further objects reside in the provision of general details of construction and in the arrangement and combination of parts for attaining the result sought by the leading object. Still other objects not at this time appearing will be referred to hereinafter.

The invention consists of the novel constructions herein described and finally claimed.

The nature, characteristic features and scope of the invention will be more fully understood from the following description taken in connection with the accompanying drawings forming part hereof, and in which:

Fig. 1, is a view of the underside of the base of the device and illustrating the stabilizing medium in folded position.

Fig. 2, is a view in section taken upon the line 2—2 of Fig. 1, and illustrating the stabilizing medium opened out to retain the device in stationary position.

Fig. 3, is a view in perspective of one of the stabilizing mediums detached; and

Fig. 4, is a view in perspective of the tray coupling parts shown in Fig. 2, in detached relation.

For the purpose of illustrating my invention I have shown in the accompanying

drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

Referring to the drawings in detail, the device of the invention, generally stated, is comprised of a supporting structure or base and a supported structure or chair each of which are movable in unison and of which the latter has independent movement with respect to the former. The supporting structure or base is comprised of a shell 10, of bowl-like contour, made of galvanized, black-iron or other suitable sheet metal. The curvature of the shell 10 is selected with a view to securing a universal, rocking movement and in order to preclude the possibility of undue tilting the circumferential edge or rim of the shell is flanged as at 11 in a horizontal manner to act as a stop. Interiorly considered the shell 10 presents a spherical concavity and is provided with a plurality of radially disposed ribs 14 which function in two capacities, one of which is to provide shell reinforcement and the other of which will be hereinafter referred to. Located within and extended centrally thereof in a vertical manner is a tubular member or socket 15 which may be spot welded or riveted to the shell bottom. The supported structure, which may be a chair 16, is arranged to be fitted to the socket 15 within the shell so as to have movement in unison with the shell and at the same time be free for independent rotary movement or in other words the supported structure has swiveled relation with respect to the shell. Adapted for removable attachment to the chair 16 is a tray 17, see Fig. 2, in order that at desired times a child occupying the device may be fed therefrom. Fixed to the forward end of each arm of the chair is a plate

18. Carried by each plate is a socket 19 provided with a set-screw 20. Secured to the underside of the tray, one upon each side, are pins 21 shaped to removably engage the sockets 19 of the plates 18 and adapted to be secured in the position shown in Fig. 2, by means of the set-screws 20. Thus the tray 17 may be conveniently and quickly positioned at the chair front when it is desired, for instance to feed a child using the device. At such times it is highly desirable to maintain the base or bowl of the device stationary as is readily apparent. In order to secure such functioning of parts use is made of a plurality of stabilizing mediums, as pivoted legs 22 of which there are three. The legs are stamped from metal and are each pivoted at 23 to the vertical ears 24 of a horizontal plate 25. The plates 25 may be welded or otherwise secured to the underside face of the base or bowl of the device. In practice good results are obtained by forming upon the said under face a recessed or depressed portion 26 for each pivotal leg. Thus as shown in Fig. 1, these legs may be caused to closely hug the under face of the base or bowl in inoperative position so as not to interfere with any rocking movement of the base. As shown in Fig. 2, the legs in operative or stabilizing position are moved outwardly from said recessed parts so that the free ends thereof abut against the floor or ground to maintain the base stationary. In the connection it is to be noted that the ears 24 function to prevent undue outward movement of the legs, see Fig. 3.

As an example the stabilizer instead of being attached directly to the under face of the base of the device may be of any other desired construction. Thus a detached stabilizer frame may be provided to rest upon the floor or ground and support the base in stationary position irrespective of whether a seat, chair or other article is supported within the bowl. Then, too, it may be desired to maintain the base stationary at times other than when a tray is being used upon the chair. As an example it may be desired to support within the bowl a device upon which a baby may recline at which time obviously the bowl should be maintained stationary. Therefore, it is apparent that stabilizing of a base for a device of the character under discussion in its broadest aspect may be for varied purposes and may be of varied construction. It is therefore to be understood that I have in mind construction other than three pivotal legs, as above described, although from a manufacturing viewpoint this is a most desirable construction. Obviously the tray above described may also be attached to a chair or seat in varied ways.

It will now be apparent that I have devised a novel and useful construction which

embodies the features of advantage enumerated as desirable in the statement of the invention and the above description and while I have in the present instance shown and described the preferred embodiment thereof which has been found in practice to give satisfactory and reliable results, it is to be understood that the same is susceptible of modification in various particulars without departing from the spirit or scope of the invention or sacrificing any of its advantages.

What I claim is:

1. A device of the character stated comprising a bowl-like shell having spherical inner and outer surfaces to permit of a universal free rocking movement, a seat arranged within the shell for free rotary movement and relatively short means within and positively secured to the shell bottom for supporting said seat which seat is relatively small as compared to the shell and is so disposed with respect to the shell that the feet of an occupant thereof are free to at all times engage the inner concaved wall of said shell to accomplish rocking of the shell and rotation of the seat, and means attached to the underside of said shell adapted to be opened out to provide a stabilizer for said device.

2. A device of the character stated comprising a bowl-like shell having spherical inner and outer surfaces to permit of a universal free rocking movement, a seat arranged within the shell for free rotary movement and relatively short means within and positively secured to the shell bottom for supporting said seat which seat is relatively small as compared to the shell and is so disposed with respect to the shell that the feet of an occupant thereof are free to at all times engage the inner concaved wall of said shell to accomplish rocking of the shell and rotation of the seat and means including pivotal feet attached to the underside of said shell to provide a stabilizer for said device.

3. A device of the character stated comprising a bowl-like shell having spherical inner and outer surfaces to permit of a universal free rocking movement, a seat arranged within the shell for free rotary movement and relatively short means within and positively secured to the shell bottom for supporting said seat which seat is relatively small as compared to the shell and is so disposed with respect to the shell that the feet of an occupant thereof are free to at all times engage the inner concaved wall of said shell to accomplish rocking of the shell and rotation of the seat, a plurality of recesses upon the underside of said shell, and a leg pivotally arranged in each recess.

4. A device of the character stated comprising a bowl-like shell having spherical inner and outer surfaces to permit of a universal free rocking movement, a seat ar-

ranged within the shell for free rotary movement and relatively short means within and positively secured to the shell bottom for supporting said seat which seat is relatively small as compared to the shell and is so disposed with respect to the shell that the feet of an occupant thereof are free to at all times engage the inner concaved wall of said

shell to accomplish rocking of the shell and rotation of the seat, a plurality of recesses 10 upon the underside of said shell, a leg pivotally arranged in each recess, and means for limiting pivotal movement of each leg.

In testimony whereof, I have hereunto signed my name.

WILLIAM F. HUDSON.
